Primary Examiner — Elizabeth Albert*(74) Attorney, Agent, or Firm* — Brooks Kushman P.C.(57) **CLAIM**

The ornamental design for a drawing instrument holder, as shown and described.

DESCRIPTION

FIG. 1 is a front perspective view of a drawing instrument holder showing my new design;

FIG. 2 is a rear perspective view of FIG. 1;

FIG. 3 is a front elevational view of FIG. 1;

FIG. 4 is a rear elevational view of FIG. 1;

FIG. 5 is a side elevational view of FIG. 1; the other side elevational view is a mirror image of this view;

FIG. 6 is a top plan view of FIG. 1; and

FIG. 7 is a bottom plan view of FIG. 1.

FIG. 8 is a front perspective view of another embodiment of the drawing instrument holder;

FIG. 9 is a rear perspective view of FIG. 8;

FIG. 10 is a front elevational view of FIG. 8;

FIG. 11 is a rear elevational view of FIG. 8;

FIG. 12 is a side elevational view of FIG. 8; the other side elevational view is a mirror image of this view;

FIG. 13 is a top plan view of FIG. 8; and,

FIG. 14 is a bottom plan view of FIG. 8.

The broken lines in the drawings are included to show features that form no part of the claimed design.
